UNITED STATES PATENT OFFICE.

LE ROY E. HUMPHRIES, OF ATLANTA, GEORGIA, ASSIGNOR OF ONE-FOURTH TO ASA W. CANDLER, OF ATLANTA, GEORGIA.

HIGH-FREQUENCY SIGNAL-RECEIVING SYSTEM.

Application filed October 22, 1923. Serial No. 669,998.

To all whom it may concern:

Be it known that I, LE ROY E. HUMPHRIES, a citizen of the United States, residing at Atlanta, in the county of Fulton and State of Georgia, have invented certain new and useful Improvements in High-Frequency Signal-Receiving Systems, of which the following is a specification.

My invention relates broadly to radio communication, and more particularly to a radio receiving system used for the reception of high frequency current signals wherever such reception or signals are subject to interference from "static" or strays of an untuned or aperiodic character that excite the receiving system by shock excitation or by induction, leaving it free to oscillate at its own natural period or to interference offered by local transmitters in proximity of the receiving station.

One of the objects of this invention is to provide a system for the reception of signals wherein the detrimental or interfering effect of the static or stray currents is minimized or eliminated, thus providing a more reliable and efficient system for the reception of the signals.

Another object of the invention is to provide a circuit arrangement for a receiving station for enabling simultaneous transmission and reception of signals, the transmitter being located in close proximity to the receiving station but producing no interference with the functioning of the receiving apparatus.

A further object of the invention is to provide a receiving circuit arrangement having a pair of differently tuned energy collecting circuits connected to differentially coupled circuits tuned to substantially the same frequency with a separate circuit cumulatively coupled with the resultant field of the differentially coupled circuits and connected to independent radio receiving apparatus which by virtue of the differential operation of the associated circuits will respond to a selected incoming frequency to the exclusion of strays or undesired frequencies.

Another object of the invention is to provide a receiving system particularly adapted for continuous wave reception wherein a pair of differently tuned receiving circuits are balanced one against the other and a local source of oscillations supplied to each

circuit through a link circuit having branches coupled one to each of the receiving circuits and each tuned to a frequency equal to the frequency of the opposite receiving circuit, whereby a resultant beat note of substantially the same frequency in each receiving circuit is produced and undesired frequencies and strays balanced out while retaining the desired signal.

My invention will be more clearly understood from the specification hereinafter following by reference to the accompanying drawings, in which Figure 1 illustrates one form of the invention employing a link circuit between the receivers with a local oscillator arranged to operate on each of the receiving circuits; and Fig. 2 shows a form of the invention in which each of the receivers operates with self-excited oscillations for beat reception with a final detection circuit connected to each of the receiving circuits. It is understood however that I do not limit myself to the particular illustration or form given as I may adopt various forms of the circuits within the scope of my invention.

In a broad sense, the invention divides the receiving circuit into two branches, branch No. 1 and branch No. 2. It may be assumed that branch No. 1 is tuned to frequency "X", the frequency of the desired signal, while branch No. 2 is tuned to a different frequency "Y". Branch No. 1 will contain the signal currents and the static currents also. Branch No. 1 is excited or heterodyned by a locally generated frequency equal to frequency Y, the incoming frequency of branch No. 2. Branch No. 2 is excited or heterodyned by a locally generated frequency equal to frequency X, the incoming frequency of branch No. 1. The resultant frequency in each branch is the same and has very closely the same wave form for damped waves.

The two branches are balanced against each other and the interfering or static currents balanced out, leaving the signal currents unaffected. The manner in which this is done most efficiently will now be described with reference to the circuit diagram.

Referring to Figure 1, reference character 1 denotes an antenna, 3 a primary inductance, 4 a variable condenser, and 5 a ground forming one branch circuit. Similarly, branch circuit No. 2 is formed by

antenna 2, primary inductance 24, variable condenser 25, and ground 26. While I have shown the radio frequency energy collecting circuits as being formed by an antenna ground system, it will be understood that other forms of radio frequency energy collecting circuits may be employed. A tuned circuit is connected to each of the branch circuits. Secondary inductance 6 is coupled with primary inductance 3 and tuned by means of secondary condenser 7, delivering the incoming frequency to an electron tube detector circuit formed by an electron tube having grid electrode 10, plate electrode 11, and filament electrode 12 with a grid condenser and grid leak 8 connected in the grid circuit thereof. Similarly branch circuit No. 2 is provided with a tuned circuit comprising secondary inductance 23 inductively coupled with primary inductance 24, the secondary inductance 23 being tuned by variable condenser 22. An electron tube detector is connected with this secondary circuit, the detector including filament electrode 28, grid electrode 29, and plate electrode 30, with grid condenser and grid leak 27 in the grid circuit thereof.

The input circuits of the electron tubes are tuned to the frequency of the respective radio frequency energy collecting circuits to which they are coupled, which frequencies are substantially different, as will be hereinafter described. The output circuits of each of the electron tubes comprise plate battery 14, inductance 16, and variable tuning condenser 15 in the circuit of the detector connected to branch No. 1, and plate battery 20, inductance 18, and variable tuning condenser 19 in the circuit of the detector coupled to branch No. 2. The filament electrodes 12 and 28 of the tubes are heated from filament battery 13. A source of local oscillations is provided at the receiving station which may consist of an electron tube oscillator. The tube is represented as having filament electrode 52, grid electrode 54 and plate electrode 51. The grid and plate circuits of the oscillator are inter-linked by inductances 50 and 55. The plate circuit contains high voltage battery 53. A link circuit is provided which is energized by the local oscillator through inductive coupling 48 and tuning condenser 49. A pair of branch circuits are connected with the link circuit at opposite extremities thereof and arranged to supply different frequencies to the input circuits of the separate electron tube detector circuits. The branch of the link circuit including inductance 44 and tuning condenser 45 is coupled with the input circuit of the electron tube detector in branch No. 1 by means of a coil 9 in the secondary circuit. The branch of the link circuit including inductance 46 and variable tuning condenser 47 is coupled with

the input circuit of the electron tube detector in branch No. 2 by means of inductance 21 in the secondary circuit.

Inductances 16 and 18 in the output circuits of the separate electron tube detector circuits are differentially coupled and an inductance 17 is interposed in the resultant field and adjustably arranged therein for picking up energy which is not balanced out by the operation of inductances 16 and 18 one upon the other. The inductance 17 is tuned by means of variable condenser 31 and the energy delivered to an electron tube apparatus where it may be further amplified and rectified and caused to actuate any suitable responsive device.

I have illustrated an electron tube having filament electrode 33, grid electrode 32 and plate electrode 34 connected for amplification of the energy picked up by inductance 17. The output circuit of this amplifier contains primary winding 35 of a coupling transformer and plate battery 36. Secondary winding 38 is inductively coupled to the primary winding 35 and arranged to deliver energy to a rectifier circuit. The rectifier circuit may be an electron tube having filament electrode 41 grid electrode 40, and plate electrode 42 with a grid condenser and grid leak 39 in the grid circuit thereof. The filament electrodes 33 and 41 may be heated by means of filament battery 37. The plate circuit of the rectifier tube is energized from high voltage battery 36 and a responsive device, such as telephone receivers 43, is connected therein.

In describing the operation of this invention I will assume that antenna 1 is tuned to a frequency of 400 kilocycles, which is the frequency of the desired incoming signal. The corresponding secondary circuit 6 and 7 is also tuned to this frequency and the signal current is impressed on grid 10 and filament 12 in the manner shown. Antenna 2 is tuned to 300 kilocycles, thus eliminating the signal of antenna 1, which is an entirely different frequency. The corresponding secondary circuit 23 and 22 of antenna 2 is tuned to 300 kilocycles and will contain the interfering currents set up by shock excitation in antenna 2. These currents are impressed on grid 29 and filament 28 in the manner shown. Thus, antenna 1 contains the signal as well as the stray currents. Antenna 2 contains the stray currents only. It is assumed for the immediate purpose of discussion that the stray waves are non-directional and that a reasonable distance between the two antennæ will not effect the phase values of the interfering currents set up in the two antennæ. This will be discussed in more detail hereinafter.

The secondary circuit of antenna 1, together with the grid-filament circuit of the tube connected therewith, is coupled to the

link circuit by coil 9 in the secondary circuit and coil 44 of the link circuit. Coil 44 is tuned by condenser 45 so that their natural period is equal to 300 kilocycles, the 5 frequency of antenna 2. The secondary circuit of antenna 2, together with the grid-filament circuit of the tube connected therewith, is coupled to the link circuit by coil 21 in the secondary circuit and coil 46 in the 10 link circuit. Coil 46 is tuned by condenser 47 so that their natural period is equal to 400 kilocycles, the frequency of antenna 1.

The link circuit is coupled to the local oscillator in the manner shown, and coil 15 48 of the link circuit should preferably be tuned to the frequency of the local oscillator. Though not absolutely essential to operation but for best operation and greater stability, the frequency of the local 20 oscillator should be the median frequency of the two antennæ, in this case 350 kilocycles. The link circuit will, therefore, be excited by induction and forced oscillation into three major frequencies. These 25 frequencies are 300, 350, and 400 kilocycles. Thus there will be impressed on the grid 10 of the electron tube coupled to antenna 1 a local frequency of 300 kilocycles, the frequency of antenna 2. Any currents in 30 antenna 1 will react with the local frequency of 300 kilocycles so that the plate circuit of the electron tube connected to antenna 1 will contain an A. C. component, the amplitude of which will rise and fall 35 at the rate of 100 kilocycles per second. The inductance 16 in the plate circuit of this tube is tuned by condenser 15 to a frequency of 100 kilocycles. Now there will be impressed on the grid 29 of the 40 tube coupled to antenna 2 a local frequency of 400 kilocycles, the frequency of antenna 1.

Any currents in antenna 2 will react with the local frequency of 400 kilocycles so that the plate circuit of the tube connected to antenna 2 will contain an A. C. component, the amplitude of which will rise and fall at the rate of 100 kilocycles per second. The inductance 18 in the plate circuit of 45 this tube is tuned by condenser 19 to a frequency of 100 kilocycles. It will readily be seen that with reference to the static or stray currents the plate circuits of the two tubes contain the same resultant frequency and very nearly the same resultant wave form due to this frequency. Now coil 16 contains the signal currents as well as the static or stray currents. Coil 18 contains the static or stray currents only. 50 Therefore, if the two coils are coupled to a third coil 17, in such a manner that their fields oppose each other with reference to coil 17, then the static currents are balanced out and the signal currents only will be 55 impressed on coil 17, which is tuned by

condenser 31 to the frequency of 100 kilocycles. Coil 17 and condenser 31 are connected to another tube where the signal is either detected or further amplified, as shown in the diagram. The frequencies given above are arbitrary frequencies for the purpose of illustration and it is readily understood that the frequencies may be any value so long as the principle of operation disclosed herein is adhered to. 75

Fig. 2 shows another form of the invention, in which the autodyne method is used in stead of an external or local oscillator. Means are introduced in the plate circuits of each receiver for securing a reactive effect on the respective input circuits and the electron tubes produce their own beat frequencies. Inductance 56 and condenser 57 are adjusted so that the plate circuit 30 is tuned to the frequency of antenna 1. Inductance 58 and condenser 59 are adjusted so that plate circuit 11 is tuned to the frequency of antenna 2. The remainder of the circuit operates as described in connection with Fig. 1, a detector being 80 interposed in the mutually coupled circuit for actuating the responsive device 43. 85

It will also be apparent that in the description given the median or mean frequency of the two antennæ, in this case 90 350 kilocycles, will also produce the same resultant frequency in both branch circuit No. 1 and branch circuit No. 2, that is, the resultant would be in this case 50,000 cycles. But this frequency does not effect 95 coil 17 since it is tuned to 100,000 cycles.

Separate antennæ are not entirely necessary; one antenna may be divided into two branches and balanced in the manner explained, in which case the two branches are fitted with filters or tuned impedances having very low decrements. The use of one antenna avoids the problem of phase values that often arises with the use of 100 separate antennæ when the interfering static or stray wave is of a directional character. The use of one antenna has the principal disadvantage that any tuning of one branch also affects the other branch, making the tuning and operation rather difficult. This, however, is not a disadvantage in the case of a fixed communication service between two transmitting stations, for in this case, once the adjustments are made 105 they need not be changed unless the transmitter constants are changed, which is not intended. 110

It is desirable that the various couplings be made as loose as possible in order to prevent radiation of the oscillation frequencies. When using two or separate antennæ, as shown in the diagram, the two antennæ should be as close together as possible without causing any material interference because of the action of one upon the other. 115 120 125 130

If the two antennæ are a considerable distance apart, the interfering currents are apt to be out of phase with reference to time in the two antennæ and the voltage set up in one will not equal the voltage set up in the other. This is because the interfering wave will have different values of amplitude for one antenna than it will for the other. The voltage impressed on the secondary circuits of the two antennæ can be controlled by proper coupling.

In connection with phase control, some improvement can be had in this respect where conditions demand it by the use of phase control circuits in the plate circuits of the tubes connected to the two antennæ. This, however, is not necessary under average conditions for practical control of the circuit, for with properly chosen constants in the system sufficient balance of the interfering currents is secured for all practical purposes. Where only one antenna is used, all difficulty by reason of phase displacement is avoided.

In localities where static waves are propagated from some particular direction and it is desired to use two antennæ, then the two antennæ can be so placed that waves from that direction are in phase with reference to the two antennæ. It is, of course, understood that whatever types of antennæ are used, they should have as nearly as possible the same physical and electrical characteristics. The same applies to the electron tubes used in the system. In actual construction and operation the proper component parts of the system should be perfectly shielded to prevent interference between them because of electrostatic or electromagnetic induction.

My invention finds particular application where it is desired to establish simultaneous transmission and reception between two stations under conditions where it is not possible to erect the receiving station and the transmitting station at any great distance apart. In this invention the receiving antennæ need only to be placed a moderate or short distance away from the transmitting antenna and placed so that the two receiving antennæ are in proper phase relation to the waves from the transmitting antenna.

Referring back to the explanation of the operation of this invention in reference to the circuit shown in the drawing and the frequencies assumed, it will be seen that if the local transmitting station be tuned to have a frequency of 350 kilocycles, which is equal to the mean frequency of the two receiving antennæ, then the local signals will be balanced out along with the strays or static currents. The distant station would transmit at 400 kilocycles instead of 350 kilocycles and its two receiving antennæ

placed a sufficient distance away and tuned to 450 kilocycles and 350 kilocycles respectively. Thus the static currents as well as the local transmitter currents would be balanced out of both receiving circuits.

Elsewhere I have stated that the resultant frequency in the plate circuits of the two balancing electron tubes would have very nearly the same wave form. If the interfering antenna currents were induced by continuous or undamped waves, the resultant plate current frequencies would have identically the same wave form. The interfering antenna current oscillations are generally of damped form and the amount of this damping is controlled by the receiving system constants. For damped oscillations, the difference in the wave forms of the resultant frequencies in the plate circuits of the two tubes will be less the nearer the frequency of antenna 2 approaches the frequency of antenna 1, provided the decrements of the corresponding circuits are the same. The two wave forms can, of course, be varied to a certain extent by variation of coupling and resistance in the antennæ and secondary circuits.

If the two antennæ frequencies are as close together as working conditions will permit, the unbalanced potential represented by the difference in the resultant wave forms will never approach the maximum value represented by amplitudes of the interfering oscillations. The practical result of this is to effect at all times a balance of approximately 85% so that an average of only 15% of the voltage of the interfering damped oscillations remains unbalanced to effect the incoming signal.

Under certain conditions of service where very long waves are employed in transmission as in trans-oceanic wireless communication and land line carrier wave systems, the operation of this invention is simplified by the employment of small properly designed high frequency generators coupled mechanically together to produce the beat frequencies required for balancing purposes.

While I have described my invention in connection with radio reception, it will be understood that I may apply the principles of my invention to carrier wave line wire systems and that various modifications of the invention may be made, and that I intend no limitations upon the invention other than are imposed by the scope of the appended claims.

What I claim and desire to secure by Letters Patent of the United States is as follows:

1. A radio receiving system, comprising in combination a pair of electron tube circuits including input and output circuits, radio frequency energy collecting means connected to said input circuits, said input circuits being tuned to different radio fre-

- quencies and said output circuits being tuned to substantially the same frequencies, a link circuit interconnecting said input circuits, said link circuit including a local oscillator and a pair of branch circuits inductively coupled one with each input circuit and arranged to deliver a frequency equal to the frequency of the opposite input circuit, said output circuits being differentially coupled and arranged to deliver a resultant field to an independent radio receiving circuit.
2. A radio receiving system, comprising in combination a pair of electron tube circuits each including an input and output circuit, radio frequency energy collecting means connected to said input circuits, said input circuits being tuned to different radio frequencies and said output circuits being tuned to substantially the same frequency, a local oscillator having a frequency which is substantially a median frequency between said input circuits, a link circuit connected with said local oscillator, separate branch circuits included in said link circuit inductively coupled each with one of said input circuits, means in each of said branch circuits for developing oscillations of a frequency above and below the frequency of said local oscillator, means differentially coupling said output circuits, and means cumulatively coupling the resultant field of said differential coupling means with electron tube apparatus.
3. A radio receiving system, comprising in combination a pair of electron tube circuits each including an input and output circuit, radio frequency energy collecting means connected to said input circuits, said input circuits being tuned to different radio frequencies and said output circuits being tuned to substantially the same frequency, a local oscillator having a frequency which is substantially a median frequency between said input circuits, a link circuit connected with said local oscillator, separate branch circuits included in said link circuit inductively coupled each with one of said input circuits, means in each of said branch circuits for developing oscillations of a frequency above and below the frequency of said local oscillator, means differentially coupling said output circuits, and means cumulatively coupling the resultant field of said differential coupling means with electron tube apparatus.

LE ROY E. HUMPHRIES.
